UNITED STATES PATENT OFFICE.

HARRY B. DUNCAN, OF WASHINGTON, PENNSYLVANIA, ASSIGNOR TO DUNCAN & MILLER GLASS COMPANY, OF WASHINGTON, PENNSYLVANIA, A CORPORATION OF PENNSYLVANIA.

DESIGN FOR A COMBINATION CHEESE AND CRACKER DISH.

Application filed November 26, 1923. Serial No. 7,886. Term of patent 3½ years.

To all whom it may concern:

Be it known that I, HARRY B. DUNCAN, a citizen of the United States, residing at Washington, Washington County, Pennsylvania, have invented a new, original, and ornamental Design for Combination Cheese and Cracker Dish, of which the following is a specification, reference being had to the accompanying drawing, forming a part thereof, in which the figure is a perspective view of a combination cheese and cracker dish embodying my new design.

I claim:

The ornamental design for a combination cheese and cracker dish, substantially as described.

In testimony whereof I have hereunto set my hand.

HARRY B. DUNCAN.
